William Roemer,

BY *Drake & Co.* ATT'YS.

UNITED STATES PATENT OFFICE.

WILLIAM ROEMER, OF NEWARK, NEW JERSEY.

FRAME FOR TRAVELING-BAGS.

SPECIFICATION forming part of Letters Patent No. 398,541, dated February 26, 1889.

Application filed October 6, 1886. Serial No. 215,459. (No model.)

To all whom it may concern:

Be it known that I, WILLIAM ROEMER, a citizen of the United States, residing at Newark, in the county of Essex and State of New Jersey, have invented certain new and useful Improvements in Frames for Traveling-Bags; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a durable bag-frame and one more convenient for the bag-maker, and to reduce the cost of manufacture.

The invention consists in an improved bag-frame, and in the constructions and combinations of parts, substantially as will be herein-after set forth, and finally embodied in the clauses of the claim.

Referring to the accompanying drawings, in which like letters represent corresponding parts in each of the several figures thereof, Figure 1 is a side elevation of a bag-frame embodying my improvements. Fig. 2 is an enlarged detail which will be hereinafter more fully described. Fig. 3 is a section taken through line *x* in Fig. 2, and Figs. 4 and 5 are plans of certain parts in blank before being formed for the frame.

In said drawings, *a* is the outer and *a'* the inner jaw or section of a bag-frame.

b is a flat brace or bar connecting the pivotal ends of said sections.

c is a hinge-plate enlarged at one end and provided with an eye or perforation, as *i*, adapted to receive a rivet, as *d*.

The hinge-plate *c* (shown in Fig. 5) may be stamped out in a single piece of sheet metal, the holes *f f'* and *i* punched, and the enlarged end bent at, or approximately at, right angles to the body or longer portion and to the brace or bar *b*, the holes *f f'* being adapted to receive ordinary rivets, and the eye or perforation *i* to receive a hinge-pin or rivet. By bending the hinge-plate, as shown, to form an eye for

the pivotal rivet the latter is raised above the line of the brace or bar *b*, so that the said brace may lie against the bottom of the bag and the ends of the jaws be allowed room to work without wearing upon the bag-body material or being obstructed by the same.

When the hinge-plate is made of an independent piece of metal, as shown in Figs. 1, 2, 3, and 5, holes corresponding to *f f'* are punched in the flat brace or bar *b* and the hinge-plate riveted thereto. Then a rivet or hinge-pin *d* is passed through the eye of said hinge-plate, through a rivet-hole near the extremity of the inner jaw or section, through a washer, *g*, and through a rivet-hole near the extremity of the outer jaw or section, and riveted on the outside thereof, thus forming a complete hinge for the outer and inner jaws or sections, as will be understood. In order to protect and conceal said hinge, an angular piece of metal, *e*, is riveted to the flat brace or bar *b*, thus holding said piece *e* in place, said piece *e* serving to protect the hinge and the bottom of the bag and to give a presentable and finished appearance to the latter.

By the construction herein described a very stiff, durable, and convenient frame is provided, and by bending up the ends or portions enlarged to form eyes space is given for the ends of the jaws or sections to clear the protecting-piece *e* and to allow greater facility in covering said jaws or sections with leather.

Having thus fully described the invention, what I claim as new is—

The improved frame for traveling-bags herein shown, combining therein jaws or sections *a a*, a brace or bar, *b*, hinge-plates *c c*, secured thereto and having a hinge-eye, *e*, bent at or approximately at right angles to said brace or bar, and rivets *d d*, arranged above the line of the brace or bar, substantially as and for the purposes set forth.

In testimony that I claim the foregoing I have hereunto set my hand this 23d day of September, 1886.

WM. ROEMER.
